ATTORNEY

UNITED STATES PATENT OFFICE

LEE W. BURRIS, OF ERIE, ILLINOIS

ROOFING CONSTRUCTION

Application filed April 14, 1931. Serial No. 530,070.

This invention relates to roofing constructions and more particularly to a means for securing the overlapped edges of sheets of roofing material together.

6 An object of the invention is the provision of a roofing construction in which a plurality of sheets of roofing material have their adjacent ends overlapped for a restricted portion of the width and a narrow binding strip formed of roofing material folded upon itself to form a pair of superposed sections, tacks penetrating the innermost section and the overlapped ends of the sheets of roofing material and likewise a fixed portion 10 of the roof for securing the overlapped ends of the sheets to the roof, the heads of the tacks being located between the superposed sections of the binding strip with cementitious material located between the sections for securing 15 the sections of the strip together, clips of any suitable material being employed when necessary for retaining the adjacent edges of the strips in contact with each other.

This invention will be best understood 20 from a consideration of the following detailed description, in view of the accompanying drawing forming a part of the specification; nevertheless it is to be understood that the invention is not confined to the disclosure, 25 being susceptible of such changes and modifications which shall define no material departure from the salient features of the invention as expressed in the appended claims.

In the drawing:

30 Figure 1 is a vertical section of a roof showing my invention applied thereto,

Figure 2 is a transverse vertical section of a binding strip before it is folded,

35 Figure 3 is a fragmentary view in perspective of a binding strip applied to the overlapped portions of sheets of roofing material before one section of the binding strip has been secured in place,

40 Figure 4 is a fragmentary vertical section of a modified form of the binding strip,

Figure 5 is a fragmentary view in perspective of the binding strip shown in Figure 4 before the sections are secured together,

45 Figure 6 is a fragmentary vertical section

of a further modified form of binding strip, and

Figure 7 is a fragmentary view in perspective of the form shown in Figure 6 showing the sections of the binding strip before they 50 are secured together.

Referring more particularly to the drawing, 10 designates a sheathing of wood which is secured to the rafters of a roof before the sheets 11, 12 and 13 are applied. The sheets 11 and 12 have their adjacent edges 14 and 15, respectively, located in overlapped relation while sheets 11 and 13 have their adjacent edges 16 and 17, respectively, located in overlapped relation.

The binding strip, shown more particularly in Fig. 2, and generally designated by the numeral 20, is formed of a narrow strip of roofing material which is cut, as shown at 21, intermediate the longitudinal edges of the strip to form sections 22 and 23 which may be folded upon each other, as shown in Figure 1.

The section 22 is secured to either the overlapped portion 17 of the sheet 13 or to the overlapped portion 14 of the sheet 11 by means of a cement ordinarily used for the purpose. Tacks 24 are driven through the section 22 and through the overlapped portions 16 and 17 and into the sheathing 10 which is preferably made of wood. The heads 25 of the tacks 24 are located between the sections 22 and 23 and a binding cement 26 is placed between the sections 22 and 23 for aiding in securing the sections together and for retaining them in flat contact with each other. It will be seen by this construction that the heads of the tacks are made weatherproof since they are not exposed to the elements.

U-shaped clips 27 have penetrating prongs 28 forced into the outer edges 29 of the sections 22. The projecting portion of the clip is bent over the outer edge 30 of the section 23 and over the outer face of said section. These clips are spaced along the edges of the folded sections of the binding strip and are adapted to retain the sections in flat contact until the cement secures the sections together.

It is a well known fact that when the sun's rays become sufficiently hot the material in the binding strip will approximately flux with the cement so that the sections 22 and 23 of each binding strip will be formed into a unit while the lower section 22 will likewise be formed into a unit by the gradual saturation of the section 22 and the overlapped portion 17 of the sheet 17.

- 10 The clips or U-shaped members 27 are formed of soft metal and are of sufficient strength to maintain the edges of the sections together until the cement will form a complete binding for the sections. If the 15 clips should become loosened for any reason, and released from their position, after the cement has securely connected the sections together, such looseness would have no effect whatever upon the efficacy of the structure.
- 20 The construction shown in Figures 4 and 5 are substantially identical with the construction shown in Figs. 1 to 3, except that the clips 27 are not employed. In this case, the temperature is such that the adhesive will 25 rapidly secure the sections 22 and 23 together without necessitating the use of the clips.

In the construction shown in Figs. 6 and 7 it will be seen that two thin strips 35 and 30 36 are employed which are not bound by a relatively thin edge, as is shown in Figs. 1 to 5, inclusive. In this instance, however, it is necessary to employ U-shaped clips 27 and 27^a at the opposite edges of the strips 35 for aiding in retaining the strips in flat contact with each other while the cement binder has become sufficiently set to retain the sections together. However, the tacks are employed in the same manner as that 40 shown in Figs. 1 to 5, inclusive, and cement is employed for securing the strips 36 to the overlapped portion of the sheet 18. It will also be noted that the portion 17 overlaps the portion 16 of the sheet 11 and the tacks 45 in this case penetrate the sheathing 10 for securing the binding strips and the overlapped sheets onto the roof.

The roofing paper employed may be of any of the well known types such as a sufficiently strong paper which has been impregnated with an asphalt or tar in the usual manner.

I claim:

- 55 1. A binding strip for sheet roofing comprising a strip of roofing paper formed of two sections folded upon each other, tacks penetrating one of the sections and having their heads located between the sections, a cement binder located between the sections 60 for securing the same together, and metal clips penetrating an edge of one of the sections and bent over the other section for retaining the sections in flat engagement.

- 65 2. A binding strip for sheet roofing comprising a strip of roofing paper formed of

two sections folded upon each other, tacks penetrating one of the sections and having their heads located between the sections, a cement binder between the superposed sections and between the inner sections of the 70 binding strip and the material forming the roof, and means for securing the free edges of the sections together.

LEE W. BURRIS.
